P. E. HAWKINSON

LIFTING JACK

Filed Nov. 25, 1922

Inventor
Paul E. Hawkinson
By his Attorneys
Merchant & Rose

UNITED STATES PATENT OFFICE.

PAUL E. HAWKINSON, OF MINNEAPOLIS, MINNESOTA, ASSIGNOR TO KEHAWKE MANUFACTURING CO., OF MINNEAPOLIS, MINNESOTA, A CORPORATION OF MINNESOTA.

LIFTING JACK.

Application filed November 25, 1922. Serial No. 603,194.

To all whom it may concern:

Be it known that I, PAUL E. HAWKINSON, a citizen of the United States, residing at Minneapolis, in the county of Hennepin and State of Minnesota, have invented certain new and useful Improvements in Lifting Jacks; and I do hereby declare the following to be a full, clear, and exact description of the invention, such as will enable others skilled in the art to which it appertains to make and use the same.

My present invention has for its object to provide an extremely simple and highly efficient carrying and positioning attachment for lifting jacks intended for general use, but especially adapted for use in jacking up the wheels of automobiles and trucks.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a side elevation of a lifting jack having one form of the improved attachment applied thereto;

Fig. 2 is a view partly in plan and partly in section with some parts sectioned on the line 2-2 of Fig. 1;

Fig. 3 is a detail view with some parts sectioned on the line 3-3 of Fig. 1; and

Fig. 4 is a view corresponding to Fig. 1 but showing another form of the attachment.

The numeral 5 indicates, as an entirety, a lifting jack of commercial form and with the exception of a shaft 6, to the projecting end of which is attached, by a universal joint 7, a two-part folding operating rod or handle 8, the sections of which are connected by a hinge joint 9. To the outer end of the rod 8 is applied a hand crank 10 having a hinge joint 11 which permits said hand crank 10 to be folded onto the operating rod 8.

Referring first to the invention as illustrated in Figs. 1 to 3, inclusive, the numeral 12 indicates a two-part bracket, the members of which are connected and frictionally clamped onto the sides of the lifting jack 5 by a pair of nut-equipped bolts 13. These bolts 13 extend through aligned bores in the members of the bracket 12, and are lo-

cated, the one forward, and the other rearward of the standard of the lifting jack 5. By reference to Fig. 2 it will be noted that the inner face of one of the members of the bracket 12 is vertically recessed at 14 to receive the standard of the jack 5 and thereby securely hold said bracket against angular movement on the lifting jack. On each member of the bracket 12 is a trunnion 15, a perforated ear 16 and a sleeve-like lug 17.

A pair of levers 18, in the form of bell cranks, are intermediately fulcrumed on the trunnions 15 and held thereon by cotter pins 19. One of the ends of the levers 18 extend horizontally forward from the trunnions 15 and have formed therewith aligned bearings 20 in which is mounted a shaft 21, the ends of which project outward of the bearings 19 and have a pair of wheels 22 journaled thereon and held in position by cotter pins 23.

The other ends of the levers 18 project upwardly and rearwardly and are connected by coil springs 24 to the perforated ears 16. These springs 24 exert sufficient force on the levers 18 to downwardly press the wheels 22 to normally carry the lifting jack above the floor as shown in Fig. 1, but will yield and permit the lifting jack to engage the floor when under a load. The downward movement of the wheels 22, in respect to the lifting jack 5, is limited by a pair of depending stop lugs 25 on the levers 18 between said wheels and the trunnions 15 and arranged to engage the base of said jack.

An arm 26 carried by the bracket 12 is provided for limiting the lifting movement of the operating rod 8 and releasably holds said rod in a raised position, as shown in Fig. 1. As shown, this arm 26 is formed from a single rod folded upon itself, and the ends thereof are inserted in the sleeve-like lug 17 and secured by set screws 27. The intermediate portion of the rod from which the arm 26 is formed, is bent to form a yoke-like member 28, at the outer end of the arm 26, adapted to receive the rod 8. The prongs of the member 28 are in converging relation and releasably hold the rod 8 as shown in Fig. 3. By springing the prongs of the member 28 apart, the rod 8 may be detached from the arm 26.

By turning the hand crank 10 into an upright position, the joint 9 will be inverted, and in which position said joint is locked against upward pivotal movement and there-

by holds the two sections of the rod 8 obliquely aligned. In the upturned position of the hand crank 10 the same may be used as a handle; and by lifting the same, the rod 5 8, which is held by its engagement with the member 28, lifts the rear end of the jack 5 through the arm 26 from the ground and permits the same to be moved on the wheel 22 to and from a position under an axle or 10 other member to be lifted. In case the lifting jack 5 tips forward when supporting a load, the springs 24 will yield without placing any strain on the levers 18 or wheels 22.

Referring now to the invention as shown 15 in Fig. 4, the bracket is dispensed with and the trunnions 15', ears 16' and sleeve-like lugs 17' are attached or formed directly with the jack 5'.

The above described invention has, in actual usage, proven highly efficient for the purpose had in view.

What I claim is:

1. A lifting jack having a wheel-equipped lever pivoted thereto, spring means operative on the lever to downwardly press the wheel with sufficient force to tilt a jack and partially lift the same above the floor but to yield and permit the jack to engage the floor under a load, and means for operating 30 the jack and by which means the jack may be lifted and moved on said wheel.

2. The structure defined in claim 1 in further combination with a stop on the lever engageable with the jack to limit the lifting 35 movement thereof by the spring means.

3. A lifting jack having a handle connected thereto by a universal joint and provided with a vertically movable supporting wheel, yielding means downwardly pressing 40 said wheel with sufficient force to normally carry the jack above the floor but to yield and permit the jack to engage the floor under a load, and an arm attached to the jack for limiting the lifting movement of the 45 handle.

4. The structure defined in claim 3 in which the arm holds the handle in a raised position.

5. The structure defined in claim 3 in 50 which the arm is provided with yielding means for releasably holding the handle in a raised position.

6. A lifting jack having a handle connected thereto by a universal joint and provided with a vertically movable supporting wheel, yielding means downwardly pressing 55 said wheel with sufficient force to normally carry the jack above the floor but to yield and permit the jack to engage the floor under a load, an arm attached to the jack for limiting the lifting movement of the handle,

and an arm attached to the jack and having at its outer end a yoke-like member adapted to receive the handle to limit the lifting movement thereof in respect to the jack. 65

7. The structure defined in claim 6 in which the yoke-like member normally holds the handle in a raised position but will yield to release the same.

8. A lifting jack having a handle connected thereto by a universal joint and provided with a vertically movable supporting wheel, yielding means downwardly pressing said wheel with sufficient force to normally carry the jack above the floor but to yield 75 and permit the jack to engage the floor under a load, an arm attached to the jack for limiting the lifting movement of the handle, said arm comprising 80 a pair of laterally spaced members having one of their ends attached to the jack by sleeve-like lugs.

9. A lifting jack having on each side a trunnion, a pair of levers in the form of bell cranks intermediately fulcrumed on the trunnions, a pair of wheels journaled on the forwardly projecting end of the levers, a pair of springs connecting the other ends of the levers to the jack and operative on 90 said levers to downwardly press the wheels with sufficient force to carry the jack above the floor but to yield and permit the jack to engage the floor when under a load, a handle connected to the jack by a universal joint, 95 and an arm attached to the jack for limiting the lifting movement of the handle.

10. A lifting jack, a two-part bracket having means for securing the same to the jack, each member of said bracket having a trunnion, a pair of levers mounted on the trunnions, wheels journaled on the trunnions, and spring means operative on the levers to 100 downwardly press the wheels with sufficient force to carry the jack above the floor but to yield and permit the jack to engage the floor when under a load. 105

11. A lifting jack having a handle connected thereto by a universal joint, a two-part bracket having means for attaching the same to the jack, each member of the bracket having a trunnion, a pair of levers mounted on the trunnions, wheels journaled on the levers, spring means operative on the levers to 110 downwardly press the wheels with sufficient force to carry the jack above the floor but to yield and permit the jack to engage the floor under a load, and an arm attached to the bracket for limiting the lifting movement of the handle in respect to the jack. 115

In testimony whereof I affix my signature.

PAUL E. HAWKINSON.
